CLAIM

The ornamental design for a display screen with animated graphical user interface for a molding process, as shown and described.

DESCRIPTION

FIG. 1 is a first image in a sequence of a display screen with an animated graphical user interface for a molding process showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The appearance of the animated graphical user interface sequentially transitions between the images shown in FIGS. 1-7. The process or period in which one image transitions to another image forms no part of the claimed design. The outermost dash-dot-dash rectangle as well as the dash-dot-dash lines showing the monitor stand and base in all FIGS. are included for the purpose of illustrating environmental structure and form no part of the claimed design. The innermost dash-dot-dash rectangle showing the display screen as well as all other broken lines within the display screen in all FIGS. showing portions of the graphical user interface form no part of the claimed design.
